UNITED STATES PATENT OFFICE

CICERO C. BROWN, OF HOUSTON, TEXAS

CASING HEAD EQUIPMENT

Application filed January 28, 1930. Serial No. 423,926.

My invention relates to attachment for casing 1 is shown as threaded at 2 for engaging heads to be employed in producing wells for regulating the escape of gas or other fluid from the well during the changing of connection thereon.

In the flowing of oil from deep wells the upper end of the well casing is usually provided with a master valve which may be used to close the upper end of the casing.

10 The tubing within the casing, to which the oil or other liquid passes, interferes, however, with the closing of the valve. The upper end of the casing above the casing head is equipped with a series of fittings ordinarily termed a Christmas tree through which the liquid and gas may be discharged to different receptacles therefor and when these fittings are to be repaired or changed it is desirable to close the master valve.

20 In the co-pending application, Serial No. 413,475, filed December 12, 1929, I have shown a means of parting the tubing adjacent the master valve without interfering with the fittings on the Christmas tree and thus close off the passage of liquid or gas while repairs are being made.

It is an object of this invention to improve on the construction shown in the prior application and to make it possible to prevent the escape of fluid upwardly through the tubing without the necessity of closing the master valve.

I desire to provide within the movable section of the tubing a valve by which said tubing may be closed to prevent the passage of liquid therethrough. I also desire to provide on said movable section of tubing a head which is adapted to close the upper end of the casing to prevent the passage of fluid from the well to the casing head.

The invention lies particularly in an improvement upon the prior structure referred to in my application above identified whereby the passage of liquid under pressure from the well may be controlled.

Referring to the drawing herewith I have shown a side view largely in central vertical section illustrating a casing equipped with my invention.

50 In the drawing the upper end of the well

casing heads to be employed in producing wells for regulating the escape of gas or other fluid from the well during the changing of connection thereon.

The casing 1 has a seat on its inner face for a head or bushing 7 secured to the upper end of a section 8 of the tubing. The head 7 has a shoulder indicated at 9 resting upon a seat in the upper end of the casing and is thus adapted to support the weight of the tubing below. Passages 10 through this head on the tubing allows the passage of fluid therethrough from the space 11 between the casing and the tubing. The upper end of the block or bushing 7 has a downwardly tapered seat 12 thereon leading to the passage 13 through said bushing.

The upper section 14 of the tubing is adapted for adjustment vertically to move the lower end thereof to and from the seat 12. The means by which such adjustment is made will now be noted. The upper end of the casing above the master valve has a casing head 15 thereon of specific construction. There are the usual lateral outlets 16 from said casing head. The upper end thereof, however, is closed except for a central opening 17 therethrough to allow the passage of the tubing section 14. A stuffing box 18 in the upper end of the casing head about the tubing forms a fluid seal, allowing the vertical adjustment of the tubing therein. Within the casing head, below the outlet 16, the passage is slightly constricted to provide a seat 19 tapered upwardly to co-operate with the tubing section, as will be later described. The upper end of the casing head has lateral projections 20 upon which is supported a frame 21. Said frame is made up of a pair of upright legs connected at their upper ends by a spider 22. Said spider has a stuffing box 23 at its lower end to fit about the upper end 24 of the tubing section. The said tubing section projects through said stuffing box and extends upwardly into the lower end 25 of the Christmas tree 26, said member being screwed with-

80

100

in the upper end of the bushing 22 as will be seen from the drawing.

The upper tubing section 14 previously noted is provided at its lower end with a valve 5 head 28. Said head is tapered at 29 on its lower end to fit within the seat 12 and when thus seated the fluid passing upwardly from the tubing 8 is allowed to pass through the section 14 and upwardly into the fitting 25. 10 On the upper side of the valve head 28 is an upwardly tapered shoulder 30 adapted to fit against the shoulder 19 in the casing head.

The tubing section 14 is adjustable vertically through a nut 32 screwed upon the 15 threaded outer surface 33 of the tubing. Said nut is rotatable through a gear 34 thereon co-acting with a worm gear 35 upon a rotatable rod 36 mounted in the frame 21. The nut 32 is supported in a transverse member 37 in the 20 frame, the upper end of the nut having a flange 38 thereon resting upon the support 37, allowing said nut to rotate but supporting it against vertical movement. It will be obvious from this construction that the rotation 25 of the nut 32 will move the tubing section 14 in either upward or downward direction, depending upon the direction of movement of said nut.

Above the threaded portion 33 of the tubing I have provided a section 24, slightly 30 reduced in diameter to fit within the stuffing box 22, at the lower end of which is a gate valve 39, said valve being adapted to close the passage through the tubing.

In the use of my device the tubing will 35 ordinarily be adjusted with the upper section 14 moved downwardly to seat the head 28 within the seat 12 of the lower section of the tubing, thus preventing the escape of liquid from the tubing into the casing head. When it is desired to close the passage from 40 the well so as to adjust any of the connections either with the casing head or with the upper end of the tubing upon the Christmas tree, I 45 contemplate the closing of the gate valve 4 and this may be done by raising the upper section 14 of the tubing sufficiently high to allow the gate valve 4 to be moved to closed position. Sometimes it is not convenient to 50 close said gate valve and in such cases the upper section 14 is moved further up until the upper shoulder 20 on the head 28 engages within the seat 19, thus closing the passage 55 from the casing to the outlet 16 in the casing head. The passage through the tubing may then be closed through the instrumentality of the valve 39 in the tubing.

When said valve 39 is closed it will be 60 seen that the passage of fluid from the well either through the casing head or through the tubing will be entirely shut off and it will be unnecessary to close the gate valve 4.

It will be obvious that I may employ my 65 present invention without the necessity of the gate valve being used at all. In such case

the upper end of the casing may be connected directly to the casing head by an ordinary coupling rather than by the body of the master valve. This is a common construction and need not be further described.

The advantages of my present construction lie in the fact that I am enabled by the upward movement of the upper section of the tubing to close off the passage from the casing and I am then enabled to close the passage from the tubing if desired by the operation of the valve 39. It is also obvious that either one or the other of these outlets from the casing or the tubing may be closed separately without the necessity of closing the other where such operation is desired.

What I claim as new is:

1. In combination a well casing, a master valve therein, a casing head above said valve, a tubing supported in said casing, said tubing being divided adjacent the lower side of said valve into upper and lower sections, means to move said upper section upwardly to allow the closing of said valve, and means to close the space between said casing head and said tubing at the lower end of said casing head.

2. In combination a well casing, a master valve therein, a casing head above said valve, a tubing supported in said casing, said tubing being divided adjacent the lower side of said valve into upper and lower sections, means to move said upper section upwardly to allow the closing of said valve, and means to close the space between said casing head and said tubing at the lower end of said casing head.

3. In combination a well casing, a master valve therein, a casing head above said valve, a tubing supported in said casing, said tubing being divided adjacent the lower side of said valve into upper and lower sections, means to move said upper section upwardly to allow the closing of said valve, and means to close the space between said casing head and said tubing at the lower end of said casing head.

4. In combination, a well casing, a casing head thereon having lateral outlets therefrom, a well tubing in said casing, means to support said tubing in said casing, said tubing being divided above said support into upper and lower sections, means to move said upper section, and means on said upper section coacting with said casing head to close the passage of fluid from the well to said outlets.

5. In combination, a well casing, a casing head thereon having lateral outlets therefrom, a well tubing in said casing means to support said tubing in said casing but allowing a free passage of fluid thereby, said tubing being divided above said support into upper and lower sections, means to move said upper section, means on said upper section

responsive to an upward movement of said upper section co-acting with said casing head to close the said outlets.

6. In combination, a well casing, a casing head thereon having lateral outlets therefrom, a well tubing in said casing means to support said tubing in said casing but allowing a free passage of fluid thereby, said tubing being divided above said support into upper and lower sections, means to move said upper sections, means on said upper section co-acting with said casing head to close the said outlets and means to close the passage through said upper section.

15 7. In combination, a well casing, a casing head thereon having lateral outlets therefrom, a well tubing in said casing means to support said tubing in said casing, said tubing being divided above said support into upper and lower sections, means to move said upper section, means on said upper section responsive to an upward movement of said upper section co-acting with said casing head to close the said outlets, and means to close the passage through said upper section.

25 8. In combination a well casing, a casing head thereon having lateral outlets, a well tubing in said casing projecting above said casing head, means to preserve a seal about said tubing at the upper end of said casing head, means to move said tubing in said casing head, and means on said tubing co-acting with said casing head to close the passage of fluid to said outlets when said tubing is moved longitudinally in said casing head.

35 9. In combination a well casing, a casing head thereon having lateral outlets, a well tubing in said casing projecting above said casing head, means to preserve a seal about said tubing at the upper end of said casing head, means to move said tubing in said casing head, a tubular fitting above said casing head into which said tubing is adapted to telescope, and means below said fitting to close said tubing.

45 10. In combination a well casing, a casing head thereon having lateral outlets, a well tubing in said casing projecting above said casing head, means to preserve a seal about said tubing at the upper end of said casing head, means on said tubing co-acting with said casing head to close the passage of fluid to said outlets when said tubing is moved longitudinally in said casing head, and means to close said tubing above said casing head.

55 11. In combination a well casing, a casing head thereon having lateral outlets, a well tubing in said casing projecting above said casing head, means to preserve a seal about said tubing at the upper end of said casing head, said tubing being divided in said casing into upper and lower sections, a seat at the upper end of said lower section, a down-

wardly presented seat in said casing head and a valve head on said upper tubing section movable from one of said seats to the other for the purpose described.

In testimony whereof I hereunto affix my signature this 25th day of January, A. D. 1930.
